UNITED STATES PATENT OFFICE.

JOHN E. COE, OF LAKEWOOD, NEW YORK.

DESIGN FOR A VALISE.

Application filed April 3, 1928. Serial No. 26,116. Term of patent 14 years.

To all whom it may concern:

Be it known that I, JOHN E. COE, a citizen of the United States, residing at Lakewood, in the county of Chautauqua and State of New York, have invented and produced a new and original Design for a Valise, of which the following is a specification, reference being had to the accompanying drawing, forming part thereof.

The drawing represents a perspective view of my newly designed valise.

The valise shown in the drawing, being substantially rectangular in shape, is provided with covers having each three uniformly sloped walls. The covers meet over the valise in a suitable fastening and overlap the end and side walls thereof.

I claim:

The ornamental design for a valise substantially as shown and described.

JOHN E. COE.
